OLOF JACOBSON, OF STOCKHOLM, SWEDEN.

POLE SWITCH.

Application filed May 3, 1923. Serial No. 636,326.

To all whom it may concern:

Be it known that I, OLOF JACOBSON, a subject of the King of Sweden, residing at Stockholm, Sweden, have invented a new 5 and useful Improvement in Pole Switches, of which the following is a specification.

The present invention relates to an improvement in pole switches of the type often used on transformer poles of country distribution systems for enabling the transformer to be disconnected from the high-tension lines when required, and which are provided with movable contact members which are usually combined with safety 10 fuses and are supported by an arm, frame, or the like rotatably journaled to the pole at approximately half its height, so that it may be swung down for inspection or change of fuses. Owing to the prescribed great 15 height of the high-tension poles the said arm or frame has a considerable weight owing to which it is rather difficult to swing the same up and down, which swinging of the frame is usually performed by the aid 20 of a long reach rod the weight of which will, of course, add itself to the weight of the frame. In order to facilitate the swinging of the frame it has therefore been proposed to balance the same with counter- 25 weights which entails the disadvantage, however, that the load on the pole is considerably increased, and that the mounting of the frame on the pole is made more difficult, in addition to which the counter- 30 weight will be swung upwards into the vicinity of the high-tension lines, when the frame is swung down, so that the counter- 35 weight may easily touch said lines and thus cause accidents.

40 The present invention has for its purpose to avoid the said difficulties, and is broadly characterized by that the arm or frame is actuated by one or more springs which tend to balance its weight during the swinging 45 of the frame upwards and downwards and thus to facilitate such swinging. The portion of the weight of the frame which must be overcome during such swinging, varies with the different positions of the 50 frame and is greatest in its horizontal position, and the spring actuating the arm or frame is therefore suitably connected with said arm or frame in such manner that it acts upon the same with a force which is 55 increased or decreased in proportion to the varying weight of the frame in its different

positions during the swinging. The pressure of the spring on the frame being comparatively small when the frame is in its upright and approximately vertical position, 60 so that the spring can not be depended upon to maintain the contact members supported by the frame in engagement with the stationary contact members of the switch, the present invention also comprises means for securing the frame to the pole in its upright position when the movable contact members engage the stationary contact members and thus the switch is closed.

The accompanying drawing illustrates an 70 embodiment of the present invention by way of example. Fig. 1 shows a front view of a switch according to the invention mounted on a transformer pole, and Fig. 2 shows a side view of the switch. Fig. 3 75 shows to a larger scale a fractional side view. Fig. 4 shows from below the locking clamp for the reach rod.

In the drawing the pole is shown as a double pole 21 supporting in the usual manner the transformer 22 and the insulators 23 for the high-tension lines 24. Below said lines there is provided a protection frame 25 which serves to prevent the line wires from touching the switch, should the lines 80 break. The switch which is mounted immediately below the protection frame 25, consists of the stationary contact members 3 which are supported by two cross stays 26, 27, and are formed as spring forks in 85 the usual manner, and of the movable contact members 2 which consist of knives combined with cartridge fuses and are adapted to be forced into the stationary 90 spring forks and thus to connect the forks 95 of the upper row, which are connected to the high-tension lines, to the corresponding forks of the lower row which are supported by the stay 27 and connected with the high-tension terminals of the transformer 22. 100

The three movable contact members 2 are supported by a common frame 1 rotatable on a horizontal axis 15 which is supported by two bearings 12 secured to the pole at approximately half its height, so that said 105 frame may be swung down through approximately 180° for inspection and change of fuses. The swinging of the frame up and down is effected by the aid of the reach rod 8. The upper end of said rod is connected 110 by means of a joint 7 to a catch 5 turning on a horizontal pin 6 in the frame 1, so

that the catch 5 may be caused to engage the stay 27 and thus to secure the frame 1 in its upright position, in which the movable contact members 2 engage the stationary contacts 3. In said position the frame 1 bears against a stop 4 secured to the stay 27, which stop together with the catch 5 maintains the frame 1 in the position shown with full drawn lines in Fig. 2, 10 so that the frame can not be moved out of such position by the wind.

The axis of the joint 7 is perpendicular to the pin 6 on which the catch 5 turns in the frame 1, so that said catch 5 may easily 15 be moved into and out of engagement with the stay 27 by means of the rod 8, as it will only be necessary to swing the lower end of said rod 8 outwards from the pole, to the right in Fig. 1, in order to turn the 20 catch 5 out of engagement with the stay 27, and to swing said end of said rod in towards the pole for turning the catch 5 into engagement with the stay 27. The lower end of the rod 8 is afterwards locked 25 to a cross stay 16 by means of a clamp 10, shown from below in Fig. 4, which embraces the rod, and the apertured end of which may be pushed over a stud 11 which has a hole for receiving a cotter or a padlock so that the switch may be locked.

When it is desired to open the switch, but not to inspect the fuses, the frame 1 is swung out to the position illustrated in dotted and dashed lines in Fig. 2. In this 35 position the frame 1 may be locked by means of a U-shaped catch 9 secured to the rod 8 and which is brought into engagement with the stay 16, after which the rod 8 is again locked to said stay by means 40 of the clamp 10. Owing to the joints 6 and 7 the rod 8 is prevented from turning on its longitudinal axis, so that it is impossible in this manner to move the catch 9 out of engagement with the stay 16. The 45 frame 1 secured in the said position serves as a signal arm indicating at great distance that the current is off, which is advantageous as it is thus easy to make sure that the transformer is not unnecessarily connected and consumes no-load current for no 50 useful purpose.

If it is desired to inspect or replace any of the fuses the frame 1 must be swung down entirely which is also effected by 55 means of the rod 8. When the lower end of said rod is swung out from the pole the catch 5 becomes disconnected, after which the frame may be let down. The portion of the weight of the frame 1 which one will 60 have to carry by means of the rod 8, is of course increased as the frame is swung out from the pole, and becomes greatest in the horizontal position of the frame, after which it is again decreased. In order to 65 facilitate the swinging of the frame up

and down there is therefore provided, according to the invention, a strong spiral spring 17 in each bearing 12, the outer end of said spring being secured to the bearing and its inner end being secured to a pin 18 so as to tend to turn the same in counter-clockwise direction in Fig. 3. The pin 18 is journaled in the bearing 12 at a distance outside the shaft 15 of the frame 1 and carries an arm 14 which is forced by the spring against a roller or stud 13 secured to the frame 1, thus tending to swing the frame 1 upwards. The springs 17 in the two bearings 12 thus tend to counter-balance the weight of the frame 1 so that said frame will be more easily handled. Owing to the pin 18 being placed at the same height but at a distance outside the fulcrum 15 of the frame, the length of the lever arm with which the arm 14 actuates the stud 13 sliding against the same, will vary with the different positions of the frame 1, as shown in dotted and dashed lines in Fig. 3, so that said lever arm becomes shortest and thus also the pressure upwards of the 90 spring on the frame 1 greatest when the frame 1 occupies its horizontal position, whereas the length of the lever arm is increased and thus the spring pressure is decreased the more the lever is above or below its horizontal position. By giving the arms 14 a suitably curved shape it is possible in this manner to attain that the springs 17 will act upon the frame 1 with a pressure substantially proportional to the 100 varying weight of the frame 1 in its different positions during the swinging up and down of the same.

The embodiment above described and illustrated in the drawing is only to be considered as an example and may be modified in various ways without departing from the principle of the invention, which consists in placing the frame 1 under influence of spring pressure which tends to counter-balance a greater or less portion of the weight of the frame and thereby to facilitate the swinging up and down of the frame.

I. claim:

1. In a pole switch, the combination of a swinging frame and a spring actuated arm contacting with said frame and tending to urge the same upwardly, the contact of said frame and arm being slidable when said frame is swung whereby the effective length of said arm is varied, thus causing said arm to exert a varying force on said frame at different angular positions to counterbalance the weight thereof.

2. In a pole switch, the combination of stationary contact members, movable contact members, a swinging frame supporting said movable contact members, a stud on said frame, a rotatable arm bearing against said

- stud, a spring actuating said arm so as to force the same against said stud, the fulcrum of said arm being located eccentrically to and at the same height as the fulcrum of said frame, for the purpose that the length of the lever arm with which said arm acts on said stud on said frame shall vary with the different angular positions of said frame and be shortest in the horizontal position of the same, so that the pressure exerted on said frame by said spring shall vary substantially in proportion to the varying weight of the frame during its swinging.
15. 3. In a pole switch, the combination of stationary contact members, movable contact members, a swinging frame supporting said movable contact members, at least one spring actuating said frame and adapted to counter-balance its weight during the swinging of said frame, a member secured to the pole, a catch pivoted in said frame, and a reach rod attached to said catch in such manner as to enable said catch to be moved into engagement with said member by swinging said rod towards the pole.
4. In a pole switch, the combination of stationary contact members, movable contact members, a swinging frame supporting said movable contact members, and a spring

actuated arm pivoted eccentrically with respect to the fulcrum of said frame and acting on said frame with a varying force corresponding to the varying momentum of said frame when swung so as to counter-balance its weight in different angular positions.

5. In a pole switch, the combination of stationary contact members mounted at the top of the pole, a swinging frame having a length substantially equal to half the height of the pole and pivoted at one end to the pole at a point substantially half way of its height, movable contact members attached to the other end of said frame, and at least one spring acting on said frame and adapted to act as a counterweight to balance the weight of said frame when swung.

6. In apparatus of the class described, the combination of a pivoted frame adapted to be moved about its pivot from an upper vertical position through a horizontal position to a lower vertical position, and vice versa, and a spring tending to urge said frame to upper vertical position with a force decreasing during the movement of said frame from horizontal position to either of said vertical positions.

OLOF JACOBSON.
